UNITED STATES PATENT OFFICE.

DONALD McLAREN, OF FORT WILLIAM, ONTARIO, CANADA, ASSIGNOR OF ONE-HALF TO
JOHN J. ROBINSON, OF FORT WILLIAM, ONTARIO, CANADA.

CANOE MOTOR-FRAME.

1,141,196.

Specification of Letters Patent.

Patented June 1, 1915.

Application filed March 15, 1915. Serial No. 14,607.

To all whom it may concern:

Be it known that I, DONALD McLAREN, a subject of the King of Great Britain, residing at No. 351 North Syndicate avenue, Fort William, Province of Ontario, Canada, have invented certain new and useful Improvements in Canoe Motor-Frames; and I do hereby declare that the following is a full, clear, and exact description of the invention, 10 such as will enable others skilled in the art to which it appertains to make and use the same.

The invention to be hereinafter described relates to canoe motor frames.

15 In order to more clearly disclose the construction, operation, and use of the invention, reference should be had to the accompanying drawings forming part of the present application.

20 Throughout the several figures of the drawings like reference characters designate the same parts.

In the drawings: Figure 1 is a perspective side view of the frame in operative position; 25 Fig. 2 is the same raised; Fig. 3 is a stern view of a canoe with the frame applied, in lowered position; Fig. 4 is a detail of the spring suspension means for the outer frame; and Fig. 5 is a section on line 5—5 of Fig. 4 30 looking in the direction of the arrows.

The main objects of the invention are, to provide efficient, durable, easily attached, and easily constructed means for attaching motors to canoes and the like, such means 35 being so arranged as to permit lifting of the motor in case it strikes an obstruction or enters shallow water, so as to prevent any possible damage to the canoe or the motor. Also, this supporting means can be so lifted 40 as to entirely raise the propeller out of the water, when desired.

Further objects are, to provide means for supporting the weight of the motor independently of the canoe, and to provide means 45 for preventing vibration from the motor and and for preventing possible injury to the canoe when the motor drops into its original position, after raising; being an improvement on my United States Patent Number 50 1,118,208, dated November 24, 1914.

Referring to the drawings in detail, the inner frame is composed of side beams 1 connected at their inner ends by a cross piece 2 and at their outer ends by a bench 3. 55 This frame is secured to the canoe 1^a by

means of a cross bar 4 located beneath the piece 2, with its ends extending beneath the gunwales of the canoe, and securely bolted to the piece 2. By tightening the bolts connecting cross piece 2 and bar 4, these members may be made to grip the gunwales tightly, so as to firmly secure the inner frame at its inner end. Bench 3 is provided, on its under face, with blocks 5 arranged in V shape to fit the contour of the sides of the 60 canoe. These blocks fit the sides of the canoe snugly and serve to prevent any lateral or forward movement of the inner frame.

The outer frame is composed of two side beams 6 considerably longer than beams 1 of the inner frame and extending somewhat beyond the stern of the canoe, and braced by a bench 7. Near the outer end of the outer frame a suitably braced motor attaching block 8 is mounted, at a slight outward 70 angle, and adapted to receive the motor, of any suitable construction, which is attached thereto by the usual screw clamp or similar means. The inner ends of beams 6 are pivotally connected to the inner ends of beams 1 75 of the inner frame, so as to form a vertical swinging or hinged joint. The beams and bench of the outer frame are so placed as to fit snugly over this inner frame, when the outer frame is in its normal lowered position, as in Fig. 2. By this means, the outer frame is securely braced and is normally held in a horizontal position, so that the propeller and rudder are properly immersed 80 in the water a slight distance in back of the 85 canoe. In case the propeller strikes an obstacle, or the canoe runs into shallow water, the outer end of the outer frame will rise so as to permit the motor to rise, thus preventing any possible damage to the canoe or 90 the motor.

To overcome the tendency of the motor to depress the stern of the canoe, due to its weight, air chambers or flues 9 are secured to each of the beams 6, of the outer frame, 100 by means of suitable arms 10 and brackets 11. These air chambers are so placed as to rest on the surface of the water, when the motor is lowered into operative position, so as to support its weight, and are pointed at 105 their front ends so as to offer a minimum of resistance to the water. Also, they are, each, provided with a screw cap 12 to permit of their being tested to insure their being air tight.

Special means are provided to prevent vibration from the motor, or possible injury to the canoe when the motor is forced out of the water by an obstruction and drops back into its original position. Headed pins 13 are slidably mounted through the top of bench 3 through the inner frames. These pins are held raised, as in Fig. 4, by coil springs mounted thereon, beneath the bench, 10 and having their upper ends secured to the under face thereof and their lower ends secured to the lower ends of the pins. By this arrangement, when the outer frame is lowered, bench 7 thereof rests on the heads of 15 pins 13 and puts springs 14 under tension, which thus act as a spring supporting means for the outer frame and absorb all shocks and vibration.

For the purpose of lifting the outer 20 frame, for repairs or the like, a hand screw 15 is threaded through a nut 16 secured on the under face of bench 7, and provided on its lower end with a head 17 pivotally connected thereto. This head 17 rests on plate 25 18 secured at the center of the upper face of bench 3. By operating screw 15 the outer frames can be raised or lowered, as desired. As there is no connection between head 17 and plate 18 this arrangement does not in 30 any way interfere with the ordinary operation of the frame. The frames are braced by suitable strips and angle irons, and provided with suitable eyes through which are passed the lanyards for operating the rubber. The frame has been shown as applied 35 to a canoe having inside gunwales only. In the case of a canoe having outside gunwales certain obvious changes in the details of the attaching means will have to be 40 made, and I wish to include all such changes in this application wherein a preferred form only is disclosed.

It is thought that the construction, operation, and use of the invention will be clear 45 from the preceding detailed description.

Changes may be made in the construction, arrangement, and disposition of the several parts of the invention without in any way departing from the field and scope of the 50 same, and it is meant to include all such within this application wherein only a preferred form has been disclosed.

Having thus fully described my invention, what I claim as new and desire to secure by Letters Patent is:

1. In a device of the character described, 55 an inner frame, securing means therefor, an outer frame pivotally connected at its inner end to the inner end of the inner frame, spring supporting means therefor, and motor attaching means carried by the 60 said outer frame.

2. In a device of the character described, an inner frame, securing means therefor, means for bracing the inner frame and for preventing lateral movement thereof, an outer frame pivotally connected at its inner end to the inner end of the inner frame, spring supporting means therefor carried by the inner frame, and motor attaching 70 means carried by the said outer frame.

3. In a device of the character described, an inner frame, securing means therefor, means for bracing the inner frame and for preventing lateral movement thereof, an outer frame pivotally connected at its inner end to the inner end of the inner frame, spring supporting means therefor carried by the inner frame, motor attaching means carried by the said outer frame, and means 80 for supporting the weight of a motor.

4. In a device of the character described, an inner frame, securing means therefor, means for bracing the inner frame and for preventing lateral movement thereof, an outer frame pivotally connected at its inner end to the inner end of the inner frame, spring supporting means therefor carried by the inner frame, motor attaching means carried by the said outer frame, and motor 90 supporting floats carried by the said outer frame.

5. In a device of the character described, an inner frame, securing means therefor, means for bracing the inner frame and for preventing lateral movement thereof, an outer frame pivotally connected at its inner end to the inner end of the inner frame, spring supporting means therefor carried by the inner frame, motor attaching means 95 carried by the said outer frame, motor supporting floats carried by the said outer frame, and means for raising the said outer frame.

6. In a device of the character described, 105 an inner frame, securing means therefor, means for bracing the inner frame and for preventing lateral movement thereof, an outer frame pivotally connected at its inner end to the inner end of the inner frame, 110 spring supporting means therefor carried by the inner frame, motor attaching means carried by the said outer frame, motor supporting floats carried by the said outer frame, and a hand screw threaded through 115 the said outer frame and adapted to bear loosely on a plate secured on the said inner frame.

In witness whereof I have hereunto set my hand in the presence of two witnesses. 120
DONALD McLAREN.
